Victor J. Evans
BY ATTORNEY

UNITED STATES PATENT OFFICE.

GJORUP PEDERSEN, OF MASSILLON, OHIO.

POCKET UMBRELLA.

Application filed December 10, 1921. Serial No. 521,501.

To all whom it may concern:

Be it known that I, GJORUP PEDERSEN, a subject of the King of Denmark, residing at Massillon, in the county of Stark and State of Ohio, have invented new and useful Improvements in Pocket Umbrellas, of which the following is a specification.

This invention relates to folding umbrellas, and more particularly to what I term a pocket umbrella.

One of the main objects of the invention is to provide an umbrella of comparatively simple construction and operation which may be folded or collapsed so as to occupy such a small space as to be readily placed in a container of such size as to be carried in the pocket. A further object is to provide an umbrella having simple and efficient means for holding the same extended, this means also assisting in folding or collapsing of the umbrella. Further objects will appear from the detailed description.

In the drawings:—

Figure 1 is a side view of the umbrella extended; partly broken away;

Figure 2 is a sectional view through the umbrella in folded or collapsed condition;

Figure 3 is a section taken substantially on line 3—3 of Fig. 2.

The umbrella includes a rod formed of telescoping sections 1, 2, 3 and 4. Sections 2, 3 and 4 are each provided in its inner face with a longitudinally extending groove 5 which receives a lug 6 formed on the co-operating section, these grooves and lugs serving to hold the sections of the rod against relative turning movement. Sections 1, 2 and 3 are each provided with a spring catch 7. The sections of the rod are further provided with openings which, when the rod is extended, are alined to receive the outer end portions of the free arms of catches 7, these catches thus serving to lock the sections of the rod in extended relation. By forcing the catches inwardly the rod sections may be released thus permitting the rod to be telescoped as in Figure 2.

An upper sleeve 8 is mounted about section 4 of the umbrella rod and is provided at its lower end with an outwardly projecting flange 9 which fits beneath ring 10 at the upper end of a lower sleeve 11 which fits about section 3 of the umbrella rod. Sleeve 8 is provided with an opening 12 which receives the outer end portion of the free arm

of catch 7 carried by section 3 of the rod, this catch serving to lock sections 3 and 4 and sleeve 8 together. A catch 13 is carried by sleeve 11 adjacent to the upper end thereof and fits into an opening through section 3, when the umbrella is extended, so as to lock sleeve 11 against upward movement on sleeve 8.

A head 14 is secured in the upper end of section 4 and co-operates with a head plate 15 secured in the upper end of section 4 to secure the fabric covering for the ribs of the umbrella, this covering being omitted in the drawings for clearness. This head is provided in its inner face with an annular space 14^a adapted for reception of an expansion coil spring 16 mounted about section 4 and confined between head 14 and a collar 17 at the upper end of sleeve 8. Head 14, collar 17 and ring 10 are all slotted in a known manner to receive the inner end portions of the ribs of the umbrella structure, these ribs being secured in the slots by wires passed through the ends of the ribs, or in any other suitable or preferred manner.

The rib structure for supporting the fabric top or covering of the umbrella consists of a suitable number of units 18. Each of these units includes a main top rib consisting of sections 19, 20 and 21. Section 19 is secured at its inner end in head 14 and is pivoted, at its outer end, at 22 to the inner end of section 20 the outer end of which is connected by a link 23 to the inner end of section 21. An upper brace rib 24 has its inner end secured in collar 17 and is pivoted at its outer end, at 22, to sections 19 and 20. A lower brace rib 25 extends from ring 10 to outer section 21 of the top rib, this lower brace rib including an inner section 26 connected at its outer end by a knuckle joint 27 to the inner end of an outer section 28 which is pivoted at 29 to outer section 21 of the upper main rib. A coil spring 30 is secured at its inner end, by a clip 31 to section 26 and, at its outer end, by a clip 32 to section 28. As will be noted from Figure 1, the clips project below rib 25 so that the spring is positioned beneath the axis of connection 27 when the umbrella is extended and serves to hold sections 26 and 28 in alinement, the knuckle joint 27 positively limiting downward movement of section 28 beyond horizontal position. A truss brace rib 33 is con-

100
105
110

nected at its lower end to joint 27 and is pivoted at its upper end, at 34, to section 20 of the top rib.

- When the umbrella is extended the parts 5 are in the positions illustrated in Figure 1, springs 30 serving to hold the umbrella in open or extended position. By moving catch 13 and catch 7 carried by section 3 of the rod into inoperative positions, sleeve 11 10 may be slid upwardly along sleeve 8. This breaks the joint 27 and moves clip 31 above the axis of the joint, spring 30 acting to rock section 28 of rib 25 upwardly and inwardly, section 21 of the top rib 18 being moved downwardly and inwardly and truss 15 rib 33 being rocked downwardly and outwardly so that members 21, 28, 33, 20 and 26 are disposed in substantially parallel relation. Continued upward movement of sleeve 11 forces ring 10 into contact with collar 17 so as to cause upward movement of sleeve 8. This moves the inner end of the upper brace rib 24 upwardly so as to break the joint 22 thus permitting members 19 20 and 24 to fold downwardly and inwardly into substantial parallelism with the other elements of the rib structure. The various rib sections when thus folded constitute, in effect, a plurality of toggle levers which are 25 held by spring 30 against outward movement thus preventing opening of the umbrella by spring 16 which is compressed by collar 17 of sleeve 8 so as to be seated within recess 14 for substantially its full length.
- When it is desired to extend the umbrella the rod is first extended, after which sleeve 11 is moved downwardly so as to bring ring 10 into contact with flange 9 of sleeve 8. Continued downward movement of sleeve 11 30 also causes simultaneous downward movement of sleeve 8 and as the umbrella approaches open position sleeve 16 expands so as to move sleeve 11 into its lowermost position thus extending the upper portion of the rib structure 18. When sleeve 11 is moved into its lowermost position the lower portion of the rib structure is fully extended and held in extended position by spring 30, in the manner previously described.
- From the above it will be seen that I have 35 produced an umbrella of comparatively simple construction and operation which may be readily collapsed or extended and, when collapsed, occupies but very little space so as to be easily carried in the pocket.

What I claim is:—

1. In an umbrella of the character de-

scribed, a telescoping rod, means for releasably securing the sections of said rod in extended relation, an upper sleeve slideable on the rod, a lower sleeve slideable on said upper sleeve; a head at one end of the rod, a main top rib having its inner end secured to said head and consisting of a plurality of foldably connected sections, an upper brace 65 rib secured at its inner end to said upper sleeve and having its outer end hingedly connected to the top rib at one of the joints thereof, a lower brace rib secured at its inner end to said lower sleeve and having its outer 70 end hingedly connected to the top rib, said lower brace rib comprising two sections hingedly connected together, a truss brace rib hingedly connected at its outer end to the top rib and having its inner end hingedly 75 connected to the lower brace rib at the hinge connection thereof, a tension spring having its ends secured to the respective sections of the lower brace rib, said spring being positioned below the rib when the latter is extended, and means for releasably securing said lower sleeve in lowered position.

2. In an umbrella of the character described, a telescoping rod, means for releasably securing the sections of said rod in extended relation, an upper sleeve slideable on the rod, a lower sleeve slideable on said upper sleeve, means for positively limiting downward movement of the lower sleeve relative to the upper sleeve, a head secured on one 85 end of the rod, a top rib having its inner end secured to the head and consisting of a plurality of foldably connected sections, an upper brace rib secured to the inner sleeve at the upper end thereof and having its outer end hingedly secured to the top rib at one joint thereof, a lower brace rib secured at its inner end to the lower sleeve and having its outer end hingedly secured to the top rib, said lower rib comprising two 90 hingedly connected sections, a truss rib having its inner end hinged to the lower brace rib at the hinge axis thereof and its outer end hinged to the top rib, a tension spring having its ends secured to the respective 100 sections of the lower brace rib at points remote from the hinge connection between the sections of said rib, means for releasably securing the outer sleeve in lowered position, and means for releasably securing the upper 105 sleeve in lowered position.

In testimony whereof I affix my signature.

GJORUP PEDERSEN.
